EXPANDER FOR LOOSE-LEAF NOTE BOOKS

William B. Roberts, Junction City, Kans.

Application June 6, 1947, Serial No. 753,079

6 Claims. (Cl. 129—4)

1

This invention relates to improvements in loose leaf binders or note books and more particularly to an expander adapted to be included in a loose leaf binder to maintain the leaves in a squared and centered position and protect them against crumpling and excessive wear, and to maintain the covers substantially parallel when the binder is closed.

It is among the objects of the invention to provide a note book or loose leaf binder accessory, herein referred to as an "expander" which may be engaged with the binder rings in the same manner as the filler leaves, which will maintain the filler leaves in a square and centered condition relative to the binder covers, especially when the binder contains a quantity of paper materially less than its full capacity, to protect the filler leaves against wrinkling, crumpling, excessive wear at their edges and corners and from pulling out at the ring holes, which will also maintain the covers in a substantially parallel condition so that the binder will have a neat and attractive appearance and can be conveniently disposed on a shelf or in a book case, and so that several binders may be stacked, one upon the other, without slipping or falling, which expander is self-adjusting to different quantities of paper or thicknesses of the filler in the binder, is simple in construction, economical to manufacture, attractive in appearance and materially enhances the appearance of a loose leaf binder to which it is applied.

Other objects and advantages will become apparent from a consideration of the following description in conjunction with the accompanying drawings, wherein:

Figure 1 is a plan view of an expander illustrative of the invention, in extended condition.

Figure 2 is a perspective view of the improved expander in operatively folded condition.

Figure 3 is an end view of a conventional loose leaf binder illustrating the application of the improved expander thereto.

Figure 4 is a perspective view of a fragmentary portion of an expander illustrative of the invention showing certain modifications to the form of expander illustrated in Figure 2.

Figure 5 is an end elevation of a fragmentary portion of a loose leaf binder showing the application thereto of the somewhat modified form of expander illustrated in Figure 4.

With continued reference to the drawings, the conventional loose leaf binder or note book, as illustrated in Figure 3, has a back 10 to which is secured a ring retaining and locking device 11

2

carrying a plurality of rings 12 which support a filler 13 and a pair of covers 14 hinged to the edges of the back 10 to overlie respectively the opposite sides of the filler 13. The filler is made up of a plurality of paper leaves stacked in superimposed relationship and provided with openings for the rings 12.

When such a binder is filled to its capacity the outer leaves of the filler lie against the inner sides of the covers holding the covers in substantially parallel relationship to each other and the covers then protect the leaves of the filler and hold the filler in a centered and squared condition relative to the binder. However, when a thin filler, such as illustrated in Figures 3 and 5, is used, a large amount of empty space is left between the filler and the covers, the outer or free edges of the covers come together giving the binder a somewhat wedge-shape and the leaves of the filler lack support by the covers and are excessively worn at their edges and corners and frequently have the ring holes torn out of them. The wedge shape of such a partly filled binder renders it difficult to arrange a number of binders on a shelf or in a book case and makes it almost impossible to stack a number of binders one upon the other as is frequently desirable in order that they may be conveniently carried from one place to another.

The improved expander constituting the subject matter of the present invention, adjustably fills in the empty space between a filler and the covers of a loose leaf binder or note book and maintains the filler in a squared, centered condition protecting the leaves against excessive wear and damage and maintains the covers in a substantially parallel condition when the book or binder is closed so that a number of such binders may be conveniently arranged upon a shelf or in a book case or may be easily carried in stacked condition.

The expander comprises an elongated rectangular sheet 15 of resiliently pliable material, such as cardboard, fiber board or heavy multi-ply paper, such as conventionally used in manufacturing book or binder covers of limited flexibility, and hold the filler in a centered and squared conformed of the same material.

The sheet 15 is transversely folded medially of its length, as indicated at 17, to provide a pair of similar, co-extensively super-imposable inner plates provided adjacent to the medial transverse fold 17 with a plurality of elongated ring receiving openings or slots 19. The plates 18 may be individually folded or scored, as indicated at

20, parallel to the transverse medial fold 17 and between the fold 17 and the ring receiving openings 19 to provide between the united edges of the inner plate 18 a transverse portion extendable over the ring connected edge of the filler 13.

The extensions 16 constitute outer plates each joined at one edge to the free edge portion of a corresponding inner plate 18 and provided in its free edge portion with a plurality of ring receiving apertures or holes 21. The outer plates 16 may be stapled or otherwise secured to the free edge portions of the inner plates 18, as indicated at 22 in Figure 2, may be stitched to the inner plate edge portions as indicated in dotted lines in Figure 1, or may be formed integrally with the inner plate portions and provided by reversely folding the sheet 15 at the outer extremities of the inner plates, as indicated at 23 in Figure 4. If desired, the folded portion 23 may be cemented, stapled or stitched to render the reverse fold permanent so that the outer plate will be superimposed relative to the corresponding inner plate as is clearly illustrated in Figure 2.

Adjacent the junction between each associated inner and outer plate the inner plate is provided with a pair of oppositely directed spaced apart folds 24 parallel to the joined together edges of the associated plate. Each pair of folds 24 includes between them a sheet portion 25 adjustably extendable between the associated inner and outer plates so that the associated plates may adjustably separate to fill in the space between the filler and the corresponding binder covers as is clearly shown in Figure 3. The elongated ring openings or slots 19 in the inner plates provides sufficient freedom of relative movement between the associated inner and outer plates to permit the portion 25 to assume various positions of angular adjustment between the associated plates depending upon the thickness of the particular filler 13 and the width of the binder back 10.

If desired the adjusting movement of the fold included portions 25 may be facilitated by applying to the inner plate surface of the plate having the fold therein suitable spring elements 26, particularly illustrated in Figure 4, which resiliently urge the interfold portions to a position separating the associated inner and outer plates.

If desired, each outer plate may be provided adjacent the ring openings 21 with a transverse bend 27 arranged to resiliently press the ring connected end portion of the inner plate inwardly toward the filler, as particularly illustrated in Figure 5, to assist in centering the ring connected portions of the filler relative to the binder covers.

The entire device may be formed from a single piece of resiliently pliable sheet material if desired although three pieces may be used where considered desirable to facilitate the assembling. The device is thus of extremely simple construction and may be manufactured by standard paper products manufacturing methods, requiring merely punching and folding operations to produce the complete device.

The expander can thus be manufactured at extremely low costs and can be provided as standard equipment with conventional loose leaf binders at little or no increase in the cost of the binder.

The invention may be embodied in other specific forms without departing from the spirit or essential characteristics thereof. The present embodiments are, therefore, to be considered in

all respects as illustrative and not restrictive, the scope of the invention being indicated by the appended claims rather than by the foregoing description, and all changes which come within the meaning and range of equivalency of the claims, are, therefore, intended to be embraced therein.

What is claimed is:

1. An expander for use in a conventional loose leaf binder having a back, rings carried by said back to support a filler, and a pair of covers hinged to said back to respectively overlie opposite sides of said filler; said expander comprising a sheet of resiliently pliable material medially transversely folded to provide a pair of similar inner plates receiving said filler between them and having ring receiving slots adjacent said fold, and a pair of outer plates each joined along one edge to the edge of a corresponding inner plate parallel to said fold and having ring receiving holes in the free edges thereof, each inner plate having opposite, parallel folds adjacent its junction with the corresponding outer plate to provide interplate portions operative to exert resilient pressure between the sides of said filler and said covers when said binder is closed.

2. An expander for use in a conventional loose leaf binder having a back, rings carried by said back to support a filler, and a pair of covers hinged to said back to respectively overlie opposite sides of said filler; said expander comprising a sheet of resiliently pliable material medially transversely folded to provide a pair of similar inner plates receiving said filler between them and having ring receiving slots adjacent said fold, and a pair of outer plates each joined along one edge to the edge of a corresponding inner plate parallel to said fold and having ring receiving holes in the free edges thereof, each inner plate having opposite, parallel folds adjacent its junction with the corresponding outer plate to provide interplate portions operative to exert resilient pressure between the sides of said filler and said covers when said binder is closed, said ring receiving slots providing freedom of relative movement between associated plates whereby said spacer may automatically adjust itself to different filler thicknesses.

3. An expander for use in a conventional loose leaf binder having a back, rings carried by said back to support a filler, and a pair of covers hinged to said back to overlie said filler; said expander comprising an elongated rectangular sheet of resiliently pliable material medially transversely folded to provide two similar parts each of which has a transversely extending reverse fold to provide an inner and a corresponding outer plate, said sheet having ring receiving slots adjacent to and at each side of said medial folds, ring receiving holes in the end portions thereof and a pair of substantially parallel, opposite folds adjacent each reverse fold providing a portion extending between each adjoining inner and outer plate to resiliently expand said inner and outer plate into contact with said filler and said covers.

4. An expander for use in a conventional loose leaf note book having a back, rings carried by said back to support a filler, and a pair of covers hinged to said back to overlie said filler; said expander comprising two inner and two outer plates of resiliently flexible sheet material, said inner plates being joined together along corresponding edges in super-imposed co-extensive relationship and having ring receiving openings therein adjacent said joints, and each outer plate being joined to the free edge of a corresponding inner plate and super-imposable upon the inner plate, each outer

plate having ring receiving openings in the free edge portion thereof and one plate of each associated inner and outer plates having a pair of opposite folds adjacent to and substantially parallel to the joints between such associated plates to provide a portion bendable between said plates to resiliently separate said plates to fill in the space between the filler and each cover when the note book is closed.

5. An expander for use in a conventional loose leaf note book having a back, rings carried by said back to support a filler, and a pair of covers hinged to said back to overlie said filler; said expander comprising two inner and two outer plates of resiliently flexible sheet material, said inner plates being joined together along corresponding edges in super-imposed co-extensive relationship and having ring receiving openings therein adjacent said joints, and each outer plate being joined to the free edge of a corresponding inner plate and super-imposable upon the inner plate, each outer plate having ring receiving openings in the free edge portion thereof and one plate of each associated inner and outer plates having a pair of opposite folds adjacent to and substantially parallel to the joints between such associated plates to provide a portion bendable between said plates to resiliently separate said plates to fill in the space between the filler and each cover when the note book is closed, and spring elements overlying at least one of each pair of opposite folds to resi-

10 liently urge said bendable portions to plate separating position.

6. An expander for use in a conventional loose leaf note book having a back, rings carried by said back to support a filler, and a pair of covers hinged to said back to overlie said filler; said expander comprising two inner and two outer plates of resiliently flexible sheet material, said inner plates being joined together along corresponding edges in super-imposed co-extensive relationship and having ring receiving openings therein adjacent said joints, and each outer plate being joined to the free edge of a corresponding inner plate and super-imposable upon the inner plate, each outer plate having ring receiving openings in the free edge portion thereof and one plate of each associated inner and outer plates having a pair of opposite folds adjacent to and substantially parallel to the joints between such associated plates to provide a portion bendable between said plates to resiliently separate said plates to fill in the space between the filler and each cover when the note book is closed, each inner plate having a transverse bend adjacent the ring receiving openings therein to resiliently press said inner plates into contact with the portion of said filler adjacent said rings.
